CONTROL REGISTER FOR AIR CONDITIONING APPARATUS

Edwin Olson and Ernest H. Person, New Britain, Conn., assignors to Allied Thermal Corporation, New Britain, Conn., a corporation of Connecticut

Application March 21, 1956, Serial No. 572,988

3 Claims. (Cl. 98—101)

This invention relates to control registers for air conditioning apparatus of the type having fixed and movable vanes or baffles, and more particularly to a novel improved means for adjusting the movable vanes or baffles of such a register.

It is the aim of this invention to provide in a control register of the type described in U. S. Patent No. 2,082,335 issued June 1, 1937, a novel and improved means for adjusting the movable baffles thereof whereby the plane of the movable baffles will be maintained parallel with the plane of the fixed baffles in any adjusted position of the movable baffles in order to permit accurate adjustment of the register.

It is another aim of this invention that the adjusting means for the register be simple and economical to manufacture, while assuring long and trouble-free service.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a plan view of a register constructed in accordance with the invention as viewed from the upstream side thereof;

Fig. 2 is an enlarged side view of the register of Fig. 1 with a portion of the register cut away; and

Fig. 3 is an enlarged end view of the register of Fig. 1.

With reference to the drawings, a control register constructed in accordance with this invention is comprised of a hollow open ended casing 10 having a pair of side walls 11 and 12 and a pair of end walls 13 and 14 extending therebetween. Mounted within the casing are a plurality of fixed elongated baffles 15 having a tear drop cross section and fixed to the side walls 11 and 12 such as by the inwardly struck tabs 16 on the side wall 11 as shown in Fig. 3. The end walls 13 and 14 are each struck inwardly as at 17 to form end baffles having a cross section substantially equal to one-half the cross section of one of the baffles 15.

Also mounted within the casing are a plurality of movable baffles 20 having a cross section similar to that of the fixed baffles 15 but extending in the opposite direction. As can be seen from Fig. 2, the baffles 20 are respectively interposed between the fixed baffles 15 and are of a diameter permitting spanning engagement with the fixed baffles to prevent flow of air through the casing when in the closed position, as shown in Fig. 2. As shown in Figs. 1 and 2, the baffles 15 and 20 are perforated and filled with fibrous material having a sound absorbent effect, such as glass wool, to provide attenuation of noises attendant to air flow past the baffles.

In order to support baffles 20 for movement relative to the fixed baffles and the casing, there is provided a frame 21 which in the preferred embodiment is comprised of a pair of spaced apart web members 22 and 23 ex-

2

tending transversely of the baffles 20 and provided with notches as at 24 which receive the trailing edges of the baffles 20 which are fixed to the web members 22, 23 by any suitable means such as welding. The web members 22, 23 are provided with aligned elongated slots such as indicated at 25 on the web member 22 for a purpose to be later explained. A second pair of web members 27 and 28 are disposed parallel with the baffles 20 and in the preferred embodiment are fixed at either 10 end to the web members 22, 23. The web members 27, 28 are also provided with aligned elongated slots extending at right angles to the slots in the web members 22, 23 as at 29 in the web member 27 for a purpose to be later explained.

15 As can be seen from Fig. 2 the movable baffles 20 lie in a plane which is parallel with the plane of the fixed baffles 15 when in the closed position and in moving the baffles 20 away from the baffles 15 or upwardly as viewed in Fig. 2 to permit flow of air through the casing it is desired to maintain the plane of the baffles 20 parallel with the plane of the baffles 15 in order to assure a predetermined and smooth air flow.

20 Therefore, in accordance with the invention, the center portion 36 of a crank member 35 having aligned crank arms 37 and 38, and aligned offset ends 39 and 40 pivotally received in apertures provided in resilient tab members 41, 42 fixed to the side walls 11 and 12, extends through and is engaged in the slots such as 25 in the web members 22, 23. The means for mounting the ends 39, 40 of the crank 35 permits easy assembly and disassembly of the crank member relative to the casing. Further in accordance with the invention, the center portion 46 of a second crank member 45 having aligned crank arms 47 and 48 and aligned offset ends 49 and 50 journaled 30 in the end walls 13 and 14 extends through and is engaged in the slots such as 29 in the web members 27, 28.

35 As should be apparent, if it is desired to move the movable baffles 20 away from the closed portion shown in Fig. 2 to permit flow of air through the casing it is merely necessary to drive one of the crank members 35 or 45 to rotate it about the pivotal axis of the ends of the crank member in a counterclockwise direction as viewed in Figs. 2 and 3, thus moving the frame 21 and baffles 20 upwardly or away from the baffles 15 as viewed in Fig. 2. 40 As the frame 21 is thus moved, the other of the crank members 35 or 45 will of course be pivoted about the longitudinal axis of its ends and because of its cooperation with the associated slots in the frame will maintain the parallel relation between the planes of the first and 45 second set of baffles during the movement of the second set. In certain applications because of the overall size of the register it might be advantageous to provide more than one crank member 35 or 45 in order to provide proper support of the movable baffles.

50 In the specific embodiment the crank member 45 is the member which is driven and to impart rotation thereto there is rotatably mounted in the end wall 13 a stub shaft 56 which is provided with a hub 57 having a keyway 58 for the driving reception of the key 59 as shown in Fig. 1. Fixed to the shaft 56 is a pinion 60 engageable with a gear segment 61 fixed to the end 49 of the crank member 45. A washer 62 fixed to the shaft 56 is engageable with a portion of the gear segment 61 under the influence of a leaf spring 65 mounted on the end wall 65 13. A screw 66 rotatably mounted in the end wall 13 is threadably engaged with the leaf spring 65 intermediate its ends whereby rotation of the screw tending to move the leaf spring toward the washer 62 will increase the frictional engagement of the washer and gear segment, thus 70 frictionally impeding rotation of the gear segment by the pinion to assure that the movable baffles 20 will remain in any adjusted position in which they are placed.

Thus it can be seen that there has been provided a novel and improved means for adjusting the movable baffles of a control register of the type described, which is simple to manufacture and operate and which is rugged in construction and will provide accurate and trouble-free performance over long periods of use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim:

1. In a control register of the type described, a hollow open ended casing, a first set of parallel spaced apart baffles fixed to the casing, a second set of spaced apart baffles respectively interposed between baffles of said first set of baffles and lying in a plane parallel to and movable toward and away from the plane of said first set, a frame to which said second set of baffles are fixed having two pairs of spaced apart aligned slots with one pair extending transversely of the baffles of said second set and with the other pair extending at right angles to said one pair, a crank member having a center portion extending through and engaging in said one pair of slots and having aligned offset ends journaled in the casing, and a second crank member disposed at right angles to the first crank member having a center portion extending through and engaged in said other pair of slots and having aligned offset ends journaled in the casing whereby when one of said crank members is pivoted about its ends to move the second set of baffles relative to said first set the other crank member maintains the parallel relation between the planes of both sets of baffles during such movement.

2. In a control register of the type described, a hollow open ended casing including a pair of side walls and a pair of end walls extending therebetween, a first set of spaced apart parallel elongated baffles fixed to the casing,

a second set of spaced apart elongated baffles respectively interposed between baffles of a fixed set of baffles and lying in a plane parallel to and movable toward and away from the plane of said first set, a frame fixed to said second set of baffles and comprising a pair of spaced apart web members extending transversely of the baffles of said second set adjacent the ends thereof and having aligned elongated slots, and a second pair of spaced apart web members extending parallel to the baffles of said second set and having aligned elongated slots extending at right angles to the slots in the first pair of web members, a crank member having a center portion extending through and engaging in the slots of said first pair of web members and having aligned offset ends pivotally mounted on the side walls of the casing, a second crank member having a center portion extending through and engaging in the slots in said second pair of web members and having aligned offset ends pivotally mounted on the end walls of the casing, and means on the casing to rotate one of said crank members about its ends to move said second set of baffles relative to said first set.

3. In a control register of the type described, a hollow open ended casing, a first set of parallel spaced apart baffles fixed to the casing, a closure member comprising a second set of spaced apart baffles respectively interposed between the baffles of the first set of baffles and parallel thereto and a frame to which the second set of baffles are fixed, said closure member being mounted in sliding engagement with the interior of the casing for movement toward and away from the first set of baffles, and a pair of crank members extending at right angles to each other and having their ends rotatably supported by the casing, said frame having a pair of spaced apart aligned slots engaging each of the crank members to maintain the closure member parallel to the first set of baffles.
